SYSTEM FOR VISUAL CODE SIGNALING

Graves M. Jones, Beaumont, Tex., and
Otha A. Akin, New Orleans, La.

Application December 18, 1945, Serial No. 635,807

3 Claims. (Cl. 177—337)

1

This invention relates to a system for transmitting flash light signals.

One of the objects of the invention is to transmit an entire letter to the alphabet at one time, that is, all of the code elements of the letter are flashed simultaneously instead of at one at a time, as at present. This materially speeds up the transmission of messages.

Another object of the invention is a signaling system of the type described, using luminous tubing as a source of light, since such tubing has proven advantageous over other sources of light, for the purpose of flashing a rapid and fog penetrating signal. The term "luminous tubing," as herein employed, is designed to cover any type of tubing which emanates light when electrically energized, including tubing which has been evacuated, or tubing that has been charged with any one or mixture of various gases and vapors, all of which forms of tubing are hermetically sealed and will retain their characteristics over an indefinite time period.

Other objects of the invention will appear as the following description of a practical embodiment thereof proceeds.

In the drawings which accompany and form a part of the following specification:

Figure 1 is a front elevation of a signaling panel, including a side view of the operating switch;

Figure 2 is a view in elevation of the apparatus shown in Figure 1, the inner partitions of the panel casing being shown in broken lines;

Figure 3 is a fragmentary view showing in section one of the connectors;

Figure 4 is a side view, partly in section, of one of the supports for the luminous tubing;

Figure 5 is a diagrammatic view illustrating the electrical system.

A light transmitting signaling system such as is about to be described is generally employed in communicating between ships of a fleet or a ship and shore, and in the illustrated embodiment it is designed to use Morse or International code, which requires no more than five elements (dots or dashes) for any letter of the alphabet or number. A signal panel casing 10 is provided, which may be suitably positioned, for example, on the yard-arm of the mast, preferably in such a manner as to be orientated through an arc of 360°, permitting its face to be presented in any direction. The face 11 of the panel casing is provided with five windows or openings 12, 13, 14, 15 and 16. Back of these windows are the respective light boxes 1, 2, 3, 4 and 5, formed by a tube

2

supporting partition 17, which extends parallel to the front face 11, and separated from one another by the opaque partitions 18. Luminous tubes *a* in circular form representing dots, are supported on the front of the partition 17, confronting the respective windows. Other luminous tubes *b* are supported on the front face of the partition 17, in rectilinear form, arranged longitudinally, confronting the respective windows representing dashes. The dots and the dashes are designed to be alternatively energized.

Figure 4 shows a conventional means for supporting the tubing, consisting of a socket 19, having a perforated lug 20, adapted to be secured to the partition 17, and an insulating post 21, having one end fixed in said socket, having a convex seat 22 at its other end, against which the tubing rests, being formed with hook-like ears 23 at the ends of the concave seat and a loop of wire 24, surrounding the tubing and secured to said ears. The tubing is energized through electrical connections supported by the partition 17 and engaging the ends of the tubing. One of these connections is shown in Figure 3. It comprises a socket member 25 of insulation material, which passes through an aperture 26 in the partition 17, and having a flange 27 about its front end which rests flush against the front side of the partition 17. The socket member 25 has molded threads 28, to the rear of the partition 17, engaged by a spring nut 29 which screws up against the partition 17 and holds the socket member in position. The ends of the tubing enter associated socket members in the manner shown in Figure 3, and contact with a spring 30 in electrical contact with a binding post 31, to which the electrical wiring is connected.

The tube supports and connectors, as illustrated and described, are known devices and do not per se form part of the invention.

Referring to Figure 5, it will be noted that the partition 17 divides the panel casing into two compartments, the front compartment being divided into the light boxes, while the rear compartment forms a housing for the transformers 32 and 33, associated with the tubes *a* and *b* and the electrical wiring which leads to the transformers. The primaries of the transformers 32 and 33 are connected to a source of current which comes into the panel casing through the line wire 34 by the branch wires 35 and 36. The tubes are connected across the secondaries of the respective transformers.

The circuits are completed through the primaries of the transformers through the interme-

diary of the key switches 1a, 2a, 3a, 4a and 5a, associated with the respective tubes a and the key switches 1b, 2b, 3b, 4b and 5b, associated with the tubes b. Each switch has a wire connection to the primary of the corresponding transformer and to the opposite line wire 35' by the wires 36' and 37, the former of which is in circuit with the key switches 1a, 2a, 3a, 4a and 5a, the latter being in circuit with the switches 1b, 2b, 3b, 4b and 5b. Thus, when any switch in the a series is closed, the corresponding dot tube a will be energized, and when any switch in the b series is closed, it will energize the corresponding dash tube b. Figure 5 shows that the switches are preferably arranged as a keyboard with the corresponding switches of the a and b series in juxtaposition. One will never press these juxtaposed switches simultaneously. Consequently, the tubes exposed in any one of the windows will be alternatively illuminated.

The keyboard is readily learned, and in operation those switches are simultaneously closed which will flash the code designation of the entire letter.

The size of the panel casing is, of course, immaterial to the invention. It has been found in practice that a panel 6 feet long can be read clearly under adverse conditions at a radius of one mile, and it is obvious that the size could be increased to obtain unlimited range of visibility. The invention is not limited to the manual operation of the key switches. These could be operated mechanically, simultaneously in proper groupings and sequence of such groupings.

It will be understood that the invention is not restricted to the use of transformers as a source of power, but any source of current having a voltage high enough to instantly illuminate the necessary length of tubing used in each connection will be acceptable. Nor will it be necessary to employ a multiple of transformers, since a single source of high voltage current may be used instead, if desired.

While we have in the above description disclosed what we believe to be a preferred and practical form of the invention, it will be understood by those skilled in the art that the specific construction and arrangement of parts can be varied without departing from the scope of the invention.

What we claim as our invention is:

1. System for visual code signaling comprising

an arrangement of luminous tubes at a series of adjacent stations in number equal to the maximum number of code characters in any letter in the code alphabet, there being a different shaped

5 tube for each code character and a tube for each code character at each station in superposed relation in the direction of the line of sight, said tubes being independently electrically energized, and a control circuit for each tube including a switch,

10 said switches being adjacently arranged for convenient selective simultaneous group manipulation of the same.

2. System of visual signaling by a dot and dash code comprising an arrangement of luminous tubes

15 at a series of adjacent stations, the number of which stations equals the maximum number of code characters in any letter in the code alphabet, there being a rotund dot and a rectilinear dash tube at each station, said tubes being independently electrically energized, and a control circuit for each tube including a switch, said switches being arranged as a keyboard for convenient selective simultaneous group manipulation of the same.

20 3. System of visual signaling by a dot and dash code comprising a panel, a rectilinear arrangement of luminous tubes extending longitudinally of said panel at an adjacent series of stations in number equal to the maximum of code characters in any letter in the code alphabet, there being a dot and dash tube at each station, the dot tubes being circular and the dash tubes being straight and positioned diametrically with respect to said dot tubes in a common longitudinal line, said

30 tubes being independently electrically energized, and a control circuit for each tube including a switch, said switches being arranged as a keyboard for convenient selective simultaneous group manipulation of the same.
